COMBINATION TIRE AND WHEEL

Keizo Shimano and Norio Sato, both % Shiman Industrial Co., Ltd., 77 3-cho, Oimatsu-cho, Osaka, Japan

Filed June 2, 1969, Ser. No. 17,469
Claims priority, application Japan Mar. 13, 1969

Term of patent 14 years

Int. Cl. D12—14

U.S. Cl. D14—30

FIG. 1

FIG.2

FIG. 3

FIG. 1 is a front elevational view of a combination tire and wheel embodying our new design;

FIG. 2 is a side view;

FIG. 3 is a vertical cross section view taken centrally thereof and showing in enlargement the condition where the spokes and rim are taken off.

We claim:

The ornamental design for a combination tire and wheel, substantially as shown and described.
